UNITED STATES PATENT OFFICE.

ISIDOR DREYFUS, OF NEW YORK, N. Y.

DESIGN FOR A CURTAIN-BAND.

SPECIFICATION forming part of Design No. 13,622, dated February 20, 1883.

Application filed December 16, 1882. Term of patent 3½ years.

To all whom it may concern:

Be it known that I, ISIDOR DREYFUS, of the city, county, and State of New York, have invented and produced a new and original Design for a Curtain-Band, of which the following is a full, clear, and exact description.

Reference is to be had to the accompanying drawings, forming part of this specification, in which similar letters of reference indicate corresponding parts in both the figures.

Figure 1 represents a curtain-band of my newly-invented design, and Fig. 2 is a side view of one portion of the band.

The band is intended especially for use with heavy curtains.

The essential feature of the design consists in a series of articulated links, A, forming a chain of suitable length. The links are molds of rigid material covered with a winding of woolen, silk, or other fibrous material. The links are connected by metallic rings B, or, in place thereof, connections of any suitable character may be used. At the ends of the chain are larger rings C.

The band has a massive appearance, suitable to the style of curtains with which it is to be used, and at the same time it is highly ornamental. The fibrous covering of the links may be of any color best suited to the curtains.

I claim—

1. The design for a curtain-band, which consists of a series of connected massive links having the appearance of being wrapped with fibrous material, substantially as shown and described.

2. The design for a curtain-band, which consists of a series of massive links, A, having the appearance of being wrapped with fibrous material, and intermediate metallic connecting-links, B, substantially as shown and described.

ISIDOR DREYFUS.
